UNITED STATES PATENT OFFICE.

JAMES M. EASTHAM, OF SHREVEPORT, LOUISIANA.

DEEP-WELL PUMP.

1,221,519.

Specification of Letters Patent.

Patented Apr. 3, 1917.

Application filed January 2, 1914. Serial No. 809,884.

To all whom it may concern:

Be it known that I, JAMES M. EASTHAM, a citizen of the United States, residing at Shreveport, Caddo parish, and State of Louisiana, have invented and discovered certain new and useful Improvements in Deep-Well Pumps, of which the following is a specification.

My said invention consists in certain improvements in the details of construction and arrangement of parts of pumps for oil and other deep driven wells, whereby an efficient pump for the purpose is provided, all as will be hereinafter more fully described and claimed.

Referring to the accompanying drawings, which are made a part hereof, and on which similar reference characters indicate similar parts,

20 Figure 1 is a vertical longitudinal section through a portion of a well casing, showing the piston packing casing and other parts in elevation,

Fig. 2 a similar view showing the piston packing casing, and piston also, in section,

Fig. 3 a perspective view of the packing elements separate, and

Fig. 4 a detail view of the lower end of the piston packing casing on an enlarged scale.

In said drawings the portions marked A represent the well casing, B the piston packing casing, and C the piston rod.

The well casing A is, or may be, of any approved construction and arrangement, the lower section A¹ being formed with an internal shoulder as at a around its upper end on which the lower end of the piston packing casing is seated.

40 The piston packing casing B is cylindrical and has a section B¹ of lead or other soft metal soldered, or otherwise rigidly secured thereto, the means being indicated as 10.

The piston C is hollow and extends 45 through the piston packing casing B into the section A¹ beneath. It connects with a valve casing 11 at its top, an ordinary ball valve 12 being mounted therein. Packing material consisting of rings of felt or similar material 13 is interposed between the upper end of the lead section B¹ of the casing B and a ring 14 a distance above said section. A coiled spring 15 is mounted between said ring 14 and another ring 16

near the upper end of said casing B. Said 55 spring 15 operates to keep the packing material 13 compressed and maintain a tight packing between said piston rod C and the surrounding casing.

In assembling the parts the tapered lead 60 section B¹ of the casing B is dropped and driven tightly into the section A¹ of the well casing, the soft metal packing within shoulder a and serving to form a tight joint. A piston rod connection 16' is secured to 65 the upper end of valve casing 11.

In operation, the piston reciprocating through the packing material in the piston packing casing in coöperation with valve 12, operates in the well known manner to raise 70 the fluid from the well casing beneath the piston to the well casing above. By this construction a tight joint is maintained at all times and the piston packing and its casing may be easily removed from the well 75 casing merely by withdrawing the piston rod. The withdrawal of the piston rod operates to withdraw the entire internal structure being contained entirely within the circumference of the well casing and 80 connected therewith only at the separable joint at shoulder a, and thus rendered very convenient for repair when necessary.

Having thus fully described my said invention, what I claim as new and desire to 85 secure by Letters Patent is:

1. A deep well pump comprising a well casing formed with an inner annular shoulder, a piston adapted to operate within said casing provided with a valve, and a piston 90 packing casing surrounding said piston and formed with a tapered soft metal portion through which said piston operates, said soft metal portion being adapted to be seated and compressed within said annular 95 shoulder so as to bear closely upon said piston and form a packing therefor, substantially as set forth.

2. A deep well pump comprising a well casing formed with an internally projecting 100 circumferential shoulder near its lower end, a piston adapted to operate within said casing formed with a valve at its upper end, a piston packing casing surrounding said piston and formed on its lower end with a 105 tapered soft metal perforated tip through which said piston operates, said tapered soft metal tip being adapted to be seated and

compressed within said internal circumferential shoulder so as to bear closely upon said piston and form a packing therefor, and an additional spring-pressed packing 5 within said packing casing, substantially as set forth.

In witness whereof, I have hereunto set

my hand and seal at Shreveport, Louisiana, this 25th day of November, A. D. nineteen hundred and thirteen.

JAMES M. EASTHAM. [L.S.]
